CLAIM

The ornamental design for an automobile headlight, as shown and described.

DESCRIPTION

FIG. 1 is a perspective view of an automobile headlight; FIG. 2 is a front view thereof; FIG. 3 is a side view thereof; and, FIG. 4 is a top view thereof.

The broken lines in the drawings depict portions of the automobile headlight that form no part of the claimed design.

The drawings and descriptions represent the left side embodiment. The claim is also for a mirror image right side embodiment.
